Compact Washing Machine For Delicate Laundry,available www.yankodesign.com,announced Sep. 10, 2024[online],[site visited Jan. 31, 2025],Internet URL: <https://www.yankodesign.com/2024/09/10/the-roborock-zeo-mini-m1-ativa-2024-is-the-perfect-compact-washing-machine-for-delicate-laundry/> (Year: 2024).*

Primary Examiner — Jennifer Rivard*Assistant Examiner* — Jenny lou M Binas(74) *Attorney, Agent, or Firm* — Ware, Fressola, Barber & Barber LLP(57) **CLAIM**

The ornamental design for a washing machine with cloth dryer, as shown and described.

DESCRIPTION

FIG. 1 is a front, left-side perspective view of a washing machine with cloth dryer showing our new design;

FIG. 2 is a rear, right-side perspective view thereof;

FIG. 3 is a front elevational view thereof;

FIG. 4 is a rear elevational view thereof;

FIG. 5 is a left-side elevational view thereof;

FIG. 6 is a right-side elevational view thereof;

FIG. 7 is a top plan view thereof; and,

FIG. 8 is a bottom plan view thereof.

The broken lines shown in the drawings depict portions of the washing machine with cloth dryer that form no part of the claimed design.
